Primary Examiner — Mary Ann Calabrese*Assistant Examiner* — Mark David Wolfley(57) **CLAIM**

The ornamental design for a bed rail, as shown and described.

DESCRIPTION

FIG. 1 is a front, top, right perspective view of a bed rail showing my new design;

FIG. 2 is a rear, bottom, left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged detail view of the encircled portion labelled 9 in FIG. 1.

The dash-dash broken lines in the drawings depict portions of the bed rail that form no part of the claimed design. The dot-dash broken lines represent boundaries of the enlarged portion and form no part of the claimed design.
